UNITED STATES PATENT OFFICE.

GEORGE HENRY BERRY, OF SHELTON, ASSIGNOR TO THE DERBY SILVER COMPANY, OF DERBY, CONNECTICUT.

DESIGN FOR AN ORNAMENTAL RECEPTACLE.

SPECIFICATION forming part of Design No. 24,232, dated April 23, 1895.

Application filed March 8, 1895. Serial No. 541,061. Term of patent 7 years.

To all whom it may concern:

Be it known that I, GEORGE HENRY BERRY, a citizen of the United States, residing at Shelton, in the township of Huntington, county of 5 Fairfield, and State of Connecticut, have invented and produced a new and original Design for an Ornamental Receptacle, of which the following is a specification, reference being had to the accompanying drawing, forming part hereof, and which illustrates, in a perspective view, an ornamental receptacle embodying my design.

The leading feature of my design consists of the ornamental form and configuration of 15 the receptacle, substantially as shown in the accompanying drawing, in which it will be seen that the receptacle is of vertical spheroidal outline approximating that of an egg and that the opening to the receptacle occupies substantially the upper half of one side

of same and is surrounded by a broken edge, the whole forming a receptacle of ornamental and attractive character.

In the drawing, A designates the receptacle; B, the opening or mouth thereto, and C the 25 broken edge surrounding said opening or mouth.

The receptacle may rest upon the feet D or be suspended from the eye E, as may be desired. 30

What I claim is—

The design for an ornamental receptacle, substantially as shown and described.

Signed at Shelton, Connecticut, this 5th day of March, 1895.

GEORGE HENRY BERRY.
